UNITED STATES PATENT OFFICE.

JOHN RUTHVEN, OF INDIANAPOLIS, INDIANA.

CARBURETER.

1,089,501.

Specification of Letters Patent. Patented Mar. 10, 1914.

Application filed August 30, 1912. Serial No. 717,986.

To all whom it may concern:

Be it known that I, JOHN RUTHVEN, a citizen of the United States, residing at Indianapolis, in the county of Marion and State of Indiana, have invented a new and useful Improvement in Carbureters, of which the following is a specification.

The present invention relates to improvements in carbureters.

One object of the present invention is the provision of a carbureter in which any unnecessary moisture in the carbureted air is properly absorbed or filtered therefrom before the same is ready for delivery to the intended apparatus, as for instance an explosive engine or a lighting system, there being provided an augmenting means, whereby a less volatile liquid, as alcohol, may be supplied within the carbureter for intermixing with the usual petrol or gasoline.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings, Figure 1 is a vertical central sectional view of the complete carbureter. Fig. 2 is a detail side elevation of the air intake and "back fire" release valve taken at right angles to the showing thereof in Fig. 1.

Referring to the drawings, the numeral 18 designates a pipe which is connected at 40 19 to the cylindrical carbureter casing 20. The casing 20 is positioned upon a base 21, there being formed concentrically of the casing 20, a cylindrical tube 22, which provides a concentric flue vertically within the casing 20 with a partition 24 thereacross adjacent its upper end. Extending within the tube 22 from the lower end and to a point adjacent the under side of the partition 24, is a heating coil 25, which is fed from the radiator system of an explosive engine (not shown). The upper end of the tube 22 is sealed by the valve controlled disk 26, the valve 28 of which is held normally closed by means of the spring 27, the valve being opened by suction which is created by an explosive engine (not shown). The main disk

valve 28 is provided with a port having a valve seat, upon which seats the pressure release valve 29. The valves 28 and 29 are mounted so that the valve 28 will open by suction to admit air into the upper end of the tube 22, while the valve 29 opens in the opposite direction, due to the pressure within the tube 22, such pressure as for instance being caused by a "back fire" from the engine (not shown). This valve 29 is closed by the spring 29' and also allows for the escape of carbureted air should the pressure in the carbureter be above a predetermined pressure.

The tube 22 is provided with a plurality of perforations 30 through the wall thereof above the partition 24, so that the suction created in the pipe 31 to the engine will cause air to be drawn through the valve controlled disk 26 and by reason of the partition 24 acting as a deflector, the air will be drawn through the perforations 30 to the various chambers of the carbureter casing 20 as will presently appear.

A plurality of plates 32, each of which is provided with a vertically extending flue 33, are disposed within the casing 20, and wire gauze supporting members or diaphragms 35 are disposed between each of the plates 32. The wire mesh diaphragms 35 are separated 85 and disposed in pairs midway between the respective partitions or plates 32 and supported therebetween is a wicking 37. Each diaphragm 35 is composed of wire mesh or wire gauze.

In the upper end of the casing 20 is disposed the inlet funnel 38, whereby alcohol may be poured into the upper end of the carbureter casing through the absorbent material 37' and the upper pair of gauze diaphragms 35 to the space 39, the evaporated alcohol being due to the suction of the air drawn into the apertures 30 by the explosive engine or other medium, through the superposed layers of absorbent material and the wicking, so that any surplus moisture will be absorbed therefrom so that by the time the carbureted air passes out of the delivery pipe 31, such carbureted air is practically dried. The pipe 31 is led directly to the explosive engine (not shown) or to a storage tank (not shown).

The chamber 39 is provided with an alcohol drain cock 40 and an overflow pipe 50, the latter preventing the alcohol from flowing into flue 33, and thus commingling with the gasoline fed within said flue and the de-

livery end 17 of the gasoline supply pipe. Thus gasoline is fed through the flue 33, and the absorbent material 37 arranged in the compartment 43, and also the superposed 5 gauze diaphragms 35 disposed immediately below said compartment. The carbureted air will thus pass through the flue 33 of the second partition 32, it being drawn through the absorbent material and the various superposed diaphragms where the unnecessary moisture is extracted therefrom so that it is finally delivered in the best possible state for combustion.

In order to permit the draining off of the 15 gasoline from the lowermost level of the casing 20, a pipe 51 leads therefrom and may be directed back to the original supply tank (not shown).

What is claimed is:

- 20 1. A carbureter, including an open base, a casing disposed thereupon and provided with a concentrically disposed cylindrical tubular chamber the full length thereof, a partition disposed within said tubular chamber adjacent the upper end thereof, said chamber above the partition being provided with a plurality of apertures therethrough in communication with the upper end of said casing, a valve controlled air inlet in the upper end of said chamber for controlling the supply of air to the chamber above the partition, a plurality of partitions disposed within the casing about the tubular chamber and dividing the casing into a plurality of 25 superposed and communicating compartments, each partition being provided with a short conduit projecting upwardly therefrom to a point below the center line of its respective compartment, a liquid hydrocarbon 30 supply entering the upper compartment and concentric with the conduit of the upper partition, two spaced gauze diaphragms disposed within each compartment intermediate of the respective partitions, a carbureted air 35 bon supply entering the upper compartment and concentric with the conduit of the upper partition, two spaced gauze diaphragms disposed within each compartment intermediate of the respective partitions, a carbureted air 40 conducting pipe in communication with the lower compartment and adjacent the space between the gauze diaphragms thereof, the apertures of the tubular chamber being disposed adjacent to the space between the 45

gauze diaphragms of the upper compartment, a packing of absorbent and filtering material disposed about the gauze diaphragms in each compartment, and means for supplying a less volatile liquid fuel disposed to direct such fuel into the space between the gauze diaphragms of the upper compartment.

2. A carbureter, including a base, a cylindrical casing disposed thereupon and provided with a concentrically disposed cylindrical chamber the full length thereof, the said chamber being open at both ends, a partition disposed within said cylindrical chamber adjacent the upper end thereof, said chamber above the partition being provided with a plurality of apertures therethrough in communication with the upper end of the casing, a valve controlled inlet in the upper end of the cylindrical chamber for controlling the supply of air to the same above the 70 partition, a back pressure release valve also at the upper end of the cylindrical chamber, a plurality of partitions disposed within the casing about the tubular chamber and dividing the casing into a plurality of superposed 75 and communicating compartments, two spaced gauze diaphragms disposed within each compartment intermediate of the respective partitions, a liquid hydrocarbon supply led to the upper compartment at the 80 space between two of the diaphragms, a carbureted air conducting pipe in communication with the lower compartment and adjacent the space between the gauze diaphragms thereof, the apertures of the cylindrical 85 chamber being disposed adjacent the space between the gauze diaphragms of the upper compartment, and a packing of absorbent and filtering material disposed about the gauze diaphragms in each compartment. 90

In testimony that I claim the foregoing as my own, I have hereto affixed my signature in the presence of two witnesses.

JOHN RUTHVEN.
